UNITED STATES PATENT OFFICE

100,783

DESIGN FOR A COMBINATION ELECTRIC METER AND CONNECTION BOX

Isaac F. Kinnard, Lynnfield, Mass., assignor to
General Electric Company, a corporation of
New York

Application January 17, 1936, Serial No. 60,640

Term of patent 14 years

To all whom it may concern:

Be it known that I, Isaac F. Kinnard, a citizen of the United States, residing at Lynnfield, county of Essex, State of Massachusetts, have invented a new, original, and ornamental Design for a Combination Electric Meter and Connection Box, of which the following is a specification, reference being had to the accompanying drawing forming a part thereof.

In the drawing, Fig. 1 is a perspective view of a

combination electric meter and connection box seen from the front, showing my new design; and Fig. 2 is a side view.

I claim:

The ornamental design for a combination electric meter and connection box as shown.

In witness whereof, I have hereunto set my hand.

ISAAC F. KINNARD.
